UNITED STATES PATENT OFFICE.

OLAV ESKIL JORGENSEN, OF FOREST HILLS, NEW YORK, ASSIGNOR TO WORTHINGTON PUMP AND MACHINERY CORPORATION, OF NEW YORK, N. Y., A CORPORATION OF VIRGINIA.

INTERNAL-COMBUSTION-ENGINE PISTON.

Original application filed December 3, 1924, Serial No. 753,593. Divided and this application filed June 5, 1925. Serial No. 35,036.

This invention relates to improvements in internal combustion engine pistons, particularly adapted for engines of the Diesel or oil burning type and is a division of application No. 753,593, filed Dec. 3, 1924.

The object of the invention is to provide an improved construction of piston especially adapted for double-acting engines of the two-cycle type and particularly suitable 10 for heavy power purposes, as, for example, marine engines, the construction being such as to be of great strength but light weight and to secure proper alinement and durability with efficient cooling of the parts, 15 while the various parts of the piston may be readily assembled and disassembled.

With these objects in view, the invention will first be described in connection with the accompanying drawings showing a double-acting piston of the preferred form embodying the invention, and the features forming the invention will then be pointed out in the claims.

In the drawings—

25 Figure 1 is a vertical central section of the piston and piston rod, and

Figure 2 is a cross section on the line 2—2 of Fig. 1.

Referring to the drawings, A is the piston 30 rod which supports directly all the parts of the piston construction so that a firm and efficient support of all the parts is secured. A heavy center piece 10 is mounted on the rod A between the two pistons, preferably 35 by a rib and groove mounting 1, as shown, so that this center piece forms a rigid running member within the cylinder liners and between the pistons. This center piece 10 is split into halves for convenient applica-

40 tion, the halves being secured together by bolts 2. On opposite sides of the center piece 10 the piston rod carries enlargements or heads 11, 12 integrally formed therewith. At the upper end of the piston rod two

45 heads 11 are formed so as to provide for water circulation within the piston about the smaller portion of the rod between the heads, and the upper piston head 13 is seated upon the head 11, with the cylindrical portion 14 of the upper piston that carries the piston rings sliding on the lower head 11, with packing to prevent leakage, expansion and contraction of the piston thus

being provided for. The lower piston rod 55 enlargement or head has the lower piston head 15 seated on its end with the cylindrical portion 16 free to slide in packing on the head 12, as in the case of the upper piston. The upper and lower pistons are secured to the piston rod heads or enlargements by bolts 3 extending from the inner side of the piston rod heads into the piston heads 11, 12, the whole piston construction, with center piece 10, thus forming a single 60 unit firmly mounted upon the piston rod. 65

The piston cooling liquid is supplied in any suitable manner and passes upward through the annular space about the tube 17 within the piston rod A, and from this space through the lower side passages 4 on one side of the diaphragm 5, filling the space in head 12 about tube 17, to the interior of piston head 15 so as to circulate within the piston head and through the cylindrical portion 16 behind the running 70 portion and piston rings, and then from the upper side passages 6 in head 12 on the opposite side of diaphragm 5 to the space about tube 17 and through side passages 7 to the interior of the upper piston 13, 14, 75 circulating throughout the piston and within the running portion and past the piston rings and then through passages 8 to the rear side of the top of the piston, returning through tube 17. The whole piston, including the piston heads and the running portion carrying the piston rings are thus efficiently cooled, each piston having its own 80 circulation.

It will be obvious that by the construction of the piston as described a light yet 85 very strong piston is produced, which may be readily assembled and disassembled, while the piston is efficiently cooled, and any longitudinal expansion or contraction 90 of the piston due to temperature changes is fully provided for.

In disassembling the piston, it is necessary only to remove the entire double-acting piston and the piston rod from the cylinder, 100 take off the split center piece 10, and then, by removal of the bolts 3, each of the pistons may readily be removed and the parts disassembled.

While in the foregoing specification the 105 invention has been more particularly shown

and described as embodied in a vertical engine, it is to be understood that the invention is applicable to horizontal or inclined engines, and that the terms "upper" and 5 "lower", referring to the pistons, are to be understood as including pistons which are not above and below each other, but nearest to or farthest from the crank shaft.

It will be understood, also, that the invention is not limited to double-acting engines, but that certain features are applicable to single-acting engines and are thus claimed, although the invention is especially intended for double-acting engines 10 and certain features and combinations of parts in such a piston are specifically claimed.

What is claimed is:

1. In a double acting internal combustion engine, the combination, with a piston rod having enlarged portions, and a pair of hollow pistons each having a head secured to the corresponding enlarged portion of the piston rod and having a skirt, the skirts extending from their said heads toward each other, of a ring forming a continuation of the running portion of the piston skirts, 25 said ring overlapping both skirts exteriorly and arranged to prevent outward deflection 30 of the said skirts while permitting them to expand and contract.

2. In a double acting internal combustion engine, the combination, with a piston rod having enlarged portions, and a ring directly attached to the piston intermediate said enlarged portions, of a pair of hollow pistons each having a head secured to the corresponding enlarged portion of the piston rod and having a skirt, the skirts extending 35 from their said piston heads toward each other and being arranged to slide telescopically within the ring during expansion and contraction.

3. In a double acting internal combustion

engine, the combination, with a piston rod 45 having enlarged portions, and a ring directly attached to the piston intermediate said enlarged portions, of a pair of hollow pistons each having a head secured to the corresponding enlarged portion of the 50 piston rod and having a skirt, the skirts extending from their said piston heads toward each other and being arranged to slide telescopically within the ring during expansion and contraction, and means carried by 55 the piston rod for holding against inward deflection that portion of each skirt adjacent the ring while permitting said sliding movement of the skirts.

4. In a double-acting internal combustion 60 engine, a piston rod having enlargements or heads, a removable ring rigidly secured on the piston rod between said heads, and a piston on each side of said ring, each of said pistons consisting of a dome-shaped 65 head rigidly secured to one of the piston rod heads and a cylindrical portion forming the running portion of the piston in the cylinder and having a slidable mounting on the piston rod head to provide for expansion 70 and contraction.

5. In an internal combustion engine, a piston rod having an enlargement or head, a removable ring rigidly secured on the piston rod and forming a continuation of the 75 running portion of the piston, and a hollow piston with packing rings having its head secured to the piston rod head and having its inner portion slidably mounted on the piston rod head by a water-tight joint, and 80 cooling water passages for circulating cooling water through the piston in close proximity to the packing rings and through the head.

In testimony whereof, I have hereunto 85 set my hand.

OLAV ESKIL JORGENSEN.
